Primary Examiner — Paula Greene(74) *Attorney, Agent, or Firm* — Leason Ellis LLP(57) **CLAIM**

The ornamental design for terminal including a display and operating units, as shown and described.

DESCRIPTION

FIG. 1 is a front and top perspective view of a terminal including a display and operating units showing my new design;

FIG. 2 is a front elevation view thereof;

FIG. 3 is a top plan view thereof; and,

FIG. 4 is an end elevation view thereof.

The broken lines of FIGS. 1-4 are for illustrative purposes only and form no part of the claimed design.
